UNITED STATES PATENT OFFICE.

HARRISON P. REED, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,175,378.

Specification of Letters Patent. Patented Mar. 14, 1916.

Application filed June 13, 1913. Serial No. 773,400.

To all whom it may concern:

Be it known that I, HARRISON P. REED, a citizen of the United States, residing at Milwaukee, in the county of Milwaukee and 5 State of Wisconsin, have invented new and useful Improvements in Circuit-Controllers, of which the following is a full, clear, concise, and exact description, reference being had to the accompanying drawing, forming 10 a part of this specification.

My invention relates to improvements in circuit controllers particularly adapted to electric motors.

It has among its objects to provide a 15 troller having electro-responsive tripping means with improved means for automatically rendering said former means ineffective under certain conditions.

A further object is to provide a motor 20 controller having overload tripping means, with means for rendering said tripping means temporarily ineffective during the starting period of the motor.

A still further object is to provide a 25 troller of the aforesaid type which will be particularly applicable to alternating current motors.

Other objects and advantages of my invention will hereinafter appear.

30 For the purpose of clearly and fully disclosing my invention I shall describe the embodiment thereof diagrammatically illustrated in the accompanying drawing, it being understood that my invention is susceptible of modification.

The controller illustrated is particularly applicable to alternating current motors and is illustrated as applied to such use. I have shown the controller as applied to a three-phase alternating current motor 1, but of course it should be understood that the type of motor might be varied as desired. The controller includes an electro-responsive main switch 2 controlling the continuity of 45 the primary circuit of the motor, overload switches 3 and 4 and a relay switch 5. As will be hereinafter more fully set forth, the overload switches upon responding function to deenergize the main switch 2 to disconnect the motor from circuit, while the relay 50 5 functions to effect the closure of the switch 2 and to render the overload switches unresponsive for a definite period thereafter.

55 The main switch 2 is illustrated as of the

double-pole type having poles 6 and 7 which control the continuity of the circuit to two terminals of the motor, the third terminal of the motor being directly connected to the supply line. In addition, the switch 2 is 60 provided with two auxiliary switches 8 and 9 insulated therefrom and operated thereby. The auxiliary switch 8 is normally open and is closed upon closure of switch 2. The auxiliary switch 9 on the other hand is normally closed and is opened upon closure of 65 switch 2. The overload switches 3 and 4 are shown as of a conventional type, the same comprising normally closed switches adapted to be opened upon response of their 70 respective windings. Both overload switches are connected in series with the operating winding of main switch 2. Accordingly, response of either overload switch deenergizes the switch 2. Of course, the overload 75 devices might assume various other forms, as for example, fuses.

The relay switch 5, as illustrated, is provided with three sets of contacts 10, 11 and 12, all of which are normally open. All 80 three of these sets of contacts are adapted to be closed by energization of a solenoid 13 through the solenoid plunger 14 and suitable connections 15. A dash-pot 16 is provided to retard the descent of the plunger 85 14, thereby retarding the opening of the relay contacts for a definite time following the deenergization of the relay. The contacts 12 when closed complete the energizing circuit of main switch 2 while the contacts 90 10 and 11 when closed respectively short-circuit the operating windings of overload switches 3 and 4.

A control switch 17 is illustrated for controlling the relay and main switch, as hereinafter set forth, and a triple-pole knife switch 18 is provided for establishing connections with a three-phase supply circuit illustrated, as provided with lines 19, 20 and 21. Also, fuses 22 and 23 are illustrated for 100 protection of the control circuits, as will hereinafter clearly appear.

I shall now more fully describe the operation and functions of the controller by tracing the circuits illustrated. Assume that 105 the control switch 17 is closed. This completes a circuit from line 19 through knife switch 18, by conductor 24 through fuse 22, by conductor 25 through overload switches 4 and 3 in series, by conductor 26 through 110

switch 17, by conductors 27 and 28 through operating winding of relay 5, by conductor 29 through auxiliary switch 9 of main switch 2, by conductors 30, 31 and 32 through fuse 5 23, by conductors 33 and 34 through knife switch 18 to line 20. The relay thereupon responds, closing all three sets of contacts 10, 11 and 12 and energizing switch 2 through the contacts 12. The energizing circuit of 10 switch 2 may be traced, as already described, to conductor 27, thence by conductor 35 through the operating winding of said switch 2, by conductors 36 and 37 through relay contacts 12 to conductor 31 and thence 15 to line 20 as already traced. The switch 2 upon responding completes the motor circuit. The motor circuit may now be traced as follows: One circuit extends from line 19 through switch 18 by conductors 39 and 40 20 through relay contacts 10, thus short-circuiting the winding of overload switch 3, by conductor 41 through pole 6 of switch 2, by conductor 42 to the left hand terminal of the motor. A second circuit extends from 25 line 20 through switch 18, by conductor 34 directly to the middle terminal of the motor. A third circuit extends from line 21 through switch 18 by conductors 43 and 44 through relay contacts 11, thereby short-circuiting 30 the winding of overload switch 4, by conductor 45 through pole 7 of switch 2, by conductor 46 to the right hand terminal of the motor. Under such conditions the motor will be started with the overload windings 35 short-circuited. This renders the overload switches ineffective and thereby allows the motor to take the desired amount of current for starting purposes, without undesirable tripping by the overload devices. However, 40 the period of ineffectiveness of the overload switches is only temporary to facilitate the starting of the motor and after a definite interval the short-circuits around the overload windings are interrupted, thereby rendering 45 the overload switches effective to protect the motor against overloads during continued operation thereof. It should of course be understood that any suitable means such as "starting" fuses may be employed to protect the motor against undue surges of current during the brief period that the overload coils are short-circuited. The removal of the short-circuits around the overload is 50 accomplished in the following manner: 55 When the switch 2 closes it opens the auxiliary switch 9, which thereupon deenergizes the relay 5. The plunger 14 of relay 5 then descends against the action of the dash-pot 16 and after a definite time interval opens 60 10 and 11. The winding of overload switch 3 is then connected in circuit between conductors 39 and 41, while the winding of overload switch 4 is connected between conductors 43 and 45. The overload switches 65 are thereupon rendered responsive to over-

loads in any phase of the motor circuit. The relay 5 upon deenergization also opens the contacts 12, thereby interrupting the initial energizing circuit of main switch 2. Prior to this, however, the auxiliary switch 8 is 70 closed, thereby establishing a maintaining circuit for said switch 2 from conductor 37, by conductor 47 through auxiliary switch 8 and thence to conductor 31.

What I claim as new and desire to secure 75 by Letters Patent is:

1. In combination, a power operated circuit controller, an electro-responsive tripping device therefor and common means for effecting operation of said controller and 80 electrically rendering said device ineffective for a limited period following the operation of said controller.

2. In combination, a power operated circuit controller, an electro-responsive tripping device therefor and common means for effecting operation of said controller and 85 shunting the operating winding of said device for a limited period following the 90 operation of said controller.

3. In combination, a power operated circuit controller, an electro-responsive tripping device therefor and means operable to effect the setting of said controller and thereafter automatically returning to initial 95 position, said means electrically controlling said device to vary the sensitiveness thereof for a temporary period following the setting of said controller.

4. In combination, a power operated circuit controller, electro-responsive tripping means therefor and a device operable to effect the setting of said controller and to electrically vary the sensitiveness of said tripping means, said controller, when set, 100 effecting a further operation of said device to render said tripping means independent thereof.

5. In combination, an electro-responsive circuit controller, electro-responsive tripping means therefor, a contact device operable to effect response of said controller and to shunt said tripping means to reduce the sensitiveness thereof, said controller upon responding effecting a further operation of 110 said device to relieve said tripping means of 115 said shunt and means for retarding said latter operation of said device.

6. In combination, an electro-responsive circuit controller, electro-responsive tripping means therefor and an electro-responsive device responsive to effect the setting of said controller and to electrically vary the sensitiveness of said tripping means, said device being deenergized upon response 120 of said circuit controller and upon restoration to initial position restoring said tripping means to normal sensitiveness.

7. The combination with an overload circuit breaker having setting means con- 130

trollable from a distant point, of means controlling said former means and acting electrically on said circuit breaker to vary the sensitiveness thereof to overloads for a limited period after setting.

8. In combination, an overload circuit-breaker, and a relay for affecting setting thereof and electrically rendering the same independent of overloads and subsequently 10 operating automatically to render said circuit-breaker subject to the action of overloads.

9. In combination, a power-operated switch, an electro-responsive relay for affecting operation of said switch and deenergized by said switch when operated and an overload tripping device for said switch 15 electrically rendered ineffective by said re-

lay until its return to a predetermined position.

10. In combination, a power-operated switch, an electro-responsive relay for affecting operation of said switch and deenergized by said switch when operated and an overload tripping device for said switch 20 electrically rendered ineffective by said relay until its return to a predetermined position and means for retarding the return operation of said relay when deenergized.

In witness whereof, I have hereunto subscribed my name in the presence of two witnesses.

HARRISON P. REED.
